COIN SORTER

Bertil E. Colburn and Frank M. Blahnik,
Green Bay, Wis.

Application December 28, 1935, Serial No. 56,413

1 Claim. (Cl. 133—3)

The invention relates to improvements in coin sorters and has for its primary object the provision of an improved apparatus for sorting coins which is of simple construction and highly efficient in use.

Another object of the invention is the provision of a simple and efficient apparatus of the character indicated operating solely through the influence of gravity and therefore without working parts and thus capable of economical production.

Another object of the invention is the provision of an apparatus of the character indicated having special provisions therein for separating overlying coins of different sizes and denominations.

Other objects will appear hereinafter.

The invention consists in the combinations and arrangements of parts hereinafter described and claimed.

20 The invention will be best understood by reference to the accompanying drawing forming a part of this specification, and in which

Fig. 1 is a face view of apparatus embodying the invention shown with portions broken away 25 to illustrate underlying parts;

Fig. 2 a section taken substantially on line 2—2 of Fig. 1; and

Fig. 3 a partial section taken substantially on line 3—3 of Fig. 2.

30 The embodiment of the invention illustrated in the drawing comprises a suitable casing, preferably made of sheet metal as indicated, and having its upper front portion constituted by a downwardly and forwardly inclined glass front plate 11, as indicated.

A coin entry slot 12 is provided centrally in the top of the casing 10 immediately behind the glass plate 11 and a suitable coin chute or hopper 13, indicated by dotted lines in Fig. 1, may 40 be provided for facilitating the insertion of coins through the slot 12 in edgewise relation. A guide plate 14, preferably of sheet metal, is arranged in the casing 10 immediately behind and parallel to the glass front plate 11 so as to form a space 45 to receive the coins deposited through the slot 12. Immediately under the slot 12, the guide plate 14 is provided with a guide ledge 15, as shown, arranged in an inclined position and the lower portion of which is transversely grooved or waved 50 so as to roughen the same, as shown. The ledge 15 terminates in an elbow portion, as shown, which cooperates with a corresponding elbow ledge 16 to form a coin chute down which the deposited coins will pass edgewise, as will be readily understood. The lower reach of the ledge 16

is curved as indicated, the radius of curvature gradually increasing until the extreme lower end 17 of the ledge 16 is approximately horizontal. A plurality of coin escape slots 18, 19, 20, 21 and 22 of gradually increasing heights and decreasing 5 lengths are provided in the guide-way 14 along the lower reach of the ledge 16, as indicated in Fig. 1. The slot 18 is of a height to permit the passage therethrough of a dime, the slot 19 is of a height to permit of the passage therethrough of a penny, 10 the slot 20 is of a height to permit the passage therethrough of a nickel or five cent piece, the slot 21 is of a height to permit the passage therethrough of a quarter or twenty-five cent piece, and the slot 22 is of a height to permit the passage 15 therethrough of a half dollar or fifty cent piece.

As indicated, the upper side of each of the slots 19, 20, 21 and 22 are inclined upwardly and rearwardly with reference to the direction of travel 20 of the coins, which arrangement facilitates the tipping of the coins and the falling therethrough through the slots, as indicated at 23 in Fig. 2.

By this arrangement, when a number of coins are deposited through the hopper 13 and slot 12, 25 the same will roll down the coin chute thus provided. When they encounter the roughened portion of the ledge 15, they will be caused to bounce thereon, as indicated by the dotted lines in Fig. 1. This bouncing of the coins on the roughened surface of the ledge 15 tends to separate and free any coins of different sizes adhering to or overlying each other because obviously coins of different sizes, metals and weights will bounce differently on said roughened surface. As the coins 30 proceed down the coin chute, they are projected against the bend or elbow of the ledge 16, from which they bounce back into the lower reach of the coin chute, said bouncing again tending to separate and free adhering coins from each other 35 so that by the time the coins pass into the lower reach of the coin chute they will be separated from each other and proceed in single file. As the coins rolling down the lower reach of the chute 16 come to the respective slots 18, 19, 20, 40 21 and 22, they will tilt and fall through the first slot they come to which is of sufficient height to permit. Thus all the dimes will fall through the slot 18, all of the pennies through the slot 19, all of the nickels through the slot 20, all of the quarters through the slot 21 and all of the half dollars through the slot 22, thereby efficiently sorting said coins through the mere action of gravity thereon.

Arranged in the casing 10 immediately below 55

the slots 18, 19, 20, 21 and 22 are corresponding coin drawers 24, 25, 26, 27 and 28 to receive the coins escaping through said slots. Each of the drawers operates, as indicated, through a suitable opening provided in the casing 10 and in a suitable registering compartment 30 preferably made of sheet metal, as indicated, and provided at its top with upwardly extending wings 31 positioned as shown to receive the coins from the 10 corresponding slot and direct them into the corresponding coin drawer, as will be readily understood.

By this arrangement a simple and efficient coin sorter is provided which operates solely through the force of gravity, which is highly efficient in use and which can be economically produced. 15 The specific form and arrangement of parts set forth is a simple and effective one for the purpose.

While we have illustrated and described the preferred form of construction for carrying our invention into effect, this is capable of variation and modification without departing from the spirit of the invention. We therefore do not wish 5 to be limited to the precise details disclosed but desire to avail ourselves of such modifications and variations as fall within the scope of the appended claim.

We claim:

In a device for conveying coins to a coin sorter having means for separating face engaged coins, said means comprising an inclined guide having transverse ribs on the bottom thereof, whereby rolling coins will be repeatedly bounced to separate 15 said coins.
